UNITED STATES PATENT OFFICE.

DONALD N. MCLEOD, OF SOUTH LANCASTER, MASSACHUSETTS.

FIRE-ESCAPE.

SPECIFICATION forming part of Letters Patent No. 519,615, dated May 8, 1894.

Application filed May 1, 1893. Serial No. 472,565. (No model.)

To all whom it may concern:

Be it known that I, DONALD N. MCLEOD, a subject of the Queen of Great Britain, residing at South Lancaster, in the county of 5 Worcester and State of Massachusetts, have invented a new and useful Improvement in Fire-Escapes, of which the following is a specification.

The aim of this invention is to provide a 10 new and improved fire escape by which a person can safely slide down a rope, and by which, it will be impossible for a person to fall.

To this end, the invention consists of the 15 device described and claimed in this specification, and illustrated in the accompanying two sheets of drawings, in which—

Figure 1 is a side elevation of my improved device. Fig. 3 is a sectional elevation on line 2—2 of Fig. 1 looking toward the left. Fig. 20 3 is a side elevation from the opposite side relatively to Fig. 1, and Fig. 4 is a view illustrating the way my fire-escape is used.

My improved fire-escape embodies a non-rotatable drum and cylinder, around which 25 the rope can be turned or wound a number of times, and a spring-pressed brake normally acting on the rope so as to prevent the device from sliding down the rope.

The device also carries means by which a 30 person can be supported. When the brake is slightly released, the drum will slide in the loop in the rope, and will allow the person to gradually and safely descend to the ground.

My device is also so arranged that the same 35 can be applied to the rope at any intermediate point, and it is not necessary to get at an end of the rope to attach my improved device thereto.

Referring now to the drawings and in detail, I will specifically describe one preferred 40 form of my device.

10 and 11 represent frames or flanges, between which is formed a cylinder or drum 12. The parts constituting the main frame of my 45 device are preferably made out of wrought-iron or sheet-metal, and stamped up, struck or forged and welded into shape; although, of course, it is within the scope of my invention to make the parts out of cast-metal. Se- 50 cured to the side flange 10, as by means of screws 14, is the inlet guide 13 for the rope A, which is bent around as at 130, so as to guide

the rope nicely on to the drum or cylinder 12. I also provide an outlet guide 15, and this outlet guide 15 may be made part of the 55 side flange 11, if so desired; and this outlet guide is bent around as at 150 to partially encircle the rope, as shown, so as to nicely guide the rope away from the device.

It will be seen, that so far described, the 60 device can be easily applied to the rope; all that is necessary is to wind the rope around the drum or cylinder 12, and to place the inlet part of the rope in the guide 13, and the outlet part of the rope in the guide 15. I 65 preferably also provide means whereby the outlet part of the rope is securely held in the outlet guide 15, so that, if the person using the fire-escape should get swaying or badly shaking, the outlet rope, could not, by any means, 70 be displaced from the outlet guide. Formed or struck up from the guide 15 are the ears 17, in which ears 17 is mounted a shaft 20, and on this shaft 20 is arranged a lever or latch 18, which has an extending tongue 19, which 75 is adapted to fit into notches 16 and 160 cut in the guide 150—15, as shown. Integral with this latch 18 is the thumb-piece 21, and this thumb-piece may have an extending hollow hub 210, as shown, into which may be fit- 80 ted a spring 22, which is adapted to bear upon the side flange 11. When it is desired to place the rope in the outlet guide 15, all that is necessary is to press with the thumb on the thumb-piece 21, when the catch 18—19 85 will be moved clear of the outlet guide, so that the rope can be easily snapped into the same; and normally this latch 18—19 holds the rope in the outlet guide to prevent any possible accident. Extending out from the 90 side flange 11 are ears 23 between which may be arranged a suitable handle 24, by which a person can hold and guide himself nicely with the descending fire-escape. The side flange 11 also has an extending ear 25 which is bent 95 around and riveted as at 26, and in the loop thus formed is placed a ring 27 to which the body straps B and C are attached. The guide 13 is bent out as at 131 to form a guide in which the sliding piece 28 is adapted to move. 100 The ends of this sliding piece 28 are bent in as at 280 and 29, as shown, and fitting through the bent-in portion 29, and secured in the drum 12 is the shaft 30, on which is fitted the

spring 31, which spring 31 bears against the struck-in portion 29 and the inside of the drum 12, and thereby normally forces the shoe into engagement with the rope. Secured to this sliding piece 28 by means of screws or rivets 33 is a rack 32. Secured to the bent-in portion 280 of the sliding piece 28, by means of screws 35 is a brake or shoe 36, which bears against the incoming part of the rope A, which normally prevents the rope A from sliding around the drum 12, the spring 30 normally keeping the shoe 36 against the rope A. Fitted in the side flange 10 is a small shaft 37, on which is keyed or fastened a lever or handle 38, which handle may be held in place by means of nuts 39, as shown. Secured to the inside of the flange 10 may be arranged a bracket 40, which may be held in place by means of screws 41, and this bracket may carry the inner end of the shaft 37, as shown. Also keyed or fastened to the shaft 37 is a gear 43 which meshes with the rack 32 secured to the sliding piece 28. Thus, by means of this handle 38, the brake or shoe 36 can be lifted clear of the rope, and the rope allowed to slip around the drum or cylinder 12.

The parts are preferably so proportioned that the hand can just about grasp the handle 38 and the inlet guide 13, and thus can nicely control the brake.

A stop 44 is formed or fastened on the side flange 10, as shown, so as to limit the movement of the piece 28 and the distance which the brake can be moved clear of the rope A.

In some cases, when a comparatively large rope is used, it is necessary to move the brake a considerable distance from the drum in order to quickly pass the rope A around the drum. This can be done by springing the lever 38 past the shoulder 45 of the stop 44. The stop 44 is inclined, as shown, so that, if the person using the fire-escape should accidentally pull the handle beyond the stop, when the person released the handle, the lever 38 would run up over the inclined portion, and the brake would not, by any means, be held away from the rope.

I preferably use two straps as B and C; the strap B having small spring clips as b b; and the strap C having small spring clips as c c, which spring clips are snapped into the ring 27, as shown in Fig. 4. One of these straps as B is preferably placed so as to enable the person to sit upon it, who is using the fire-escape; and the other is passed under the arms. By this means, the two straps will form a sort of chair or support for the person, and will easily and nicely support the person.

The way my device is used is shown in Fig. 4. The device is attached to the rope by winding the rope around the drum 12, putting the inlet part of the rope in the inlet guide 13, and the outlet part of the rope in the guide 15, which is done by moving the latch 18 free, as before described. Then the

straps B and C are adjusted around the person, as shown, the top of the rope, of course being tied or fixed to some support. The rope A normally will not slip around the drum or cylinder 12, so that the person normally will not descend upon the rope.

The person using the fire-escape preferably places one hand upon the handle 24 to guide and support himself, and with the other hand grasps the handle 38, preferably placing his hand around the inlet guide 13. Then, when the person desires to descend, he moves the handle 38, and thus moves the brake or shoe away from the inlet rope. This will allow the rope to slip around the drum 12, and the device and the person to descend to the ground, the speed being regulated, of course, by the amount the brake is released from the rope.

My device is very simple and very advantageous for the purpose described, and has many advantages, among which may be enumerated that the device can be attached to the rope at any part of its whole length, and it is not necessary to find an end of the rope to attach the device. Also, when one person has descended, it will be seen that the device can be hauled back, and detached from the rope, and again reattached to any part of the rope, or to another rope, if desired; and thus, a number of persons can descend by the same device. It will also be seen that the use of two straps enables the person to be nicely supported and held while he is using the fire-escape. Further, it will be seen that, the rope running around the circumference of the cylinder or drum, friction is thereby reduced on the rope, making the wear of the same very slight and only needing a very slight brake or check on the rope to stop the descent. Also it is an important point having the device so that the same will normally not operate; as, if a person using the same should faint or meet with some accident, he will be held in his then position until the brake is again released. This also allows free use of the hands, which is important, as the person descending might become entangled with wires or trees, and by having free use of his hands, he is enabled to easily disentangle himself. Also it will be seen that the hands of the person using the fire-escape need not at all be applied to the rope. A practical use has demonstrated that my fire-escape possesses all these advantages, and is a very safe and efficient device.

The details and arrangement of the parts herein shown and described may be greatly varied by a skilled mechanic without departing from the scope of my invention as expressed in the claims.

Having thus fully described my invention, what I claim, and desire to secure by Letters Patent, is—

1. A fire escape consisting essentially of a non-rotatable drum or cylinder, about which the rope may be wound, of an inlet and outlet guide for guiding the rope to and from the

- cylinder and keeping the same on the cylinder, means whereby the person can be supported from the device, and means for checking and regulating the slip of the rope around the cylinder, the whole so arranged that the device can be applied to the rope at an intermediate point between its ends without removing or changing any part of the structure, substantially as described.
- 10 2. A fire-escape consisting essentially of a non-rotatable drum or cylinder, around which the rope may be wound, means whereby the person may be carried by the device, means for checking and regulating the slip of the rope around the drum or cylinder, inlet and outlet guides for leading the rope to and from the drum or cylinder, and a latch or catch for holding the rope in the outlet guide, substantially as described.
- 15 3. A fire-escape consisting of a non-rotatable drum or cylinder having side flanges, about which drum or cylinder a rope may be wound, inlet and outlet guides for leading the rope to and from the drum or cylinder and for holding the rope upon the cylinder, and a spring-

pressed brake as 36, normally exerting pressure upon the inlet end of the rope, substantially as described.

4. A fire-escape consisting of a drum or cylinder, around which the rope may be wound, a spring-pressed brake checking and regulating the slip of the rope around the drum, a lever for operating said brake, and a stop as 44 for limiting the movement of said brake, said stop being inclined so that by springing 35 the lever, the brake can be lifted a considerable distance from the drum, so that the rope can be easily put in place, but so that, if the lever should be in use, moved beyond the stop, that the same will run up the incline, 40 and return to its normal position, substantially as described.

In testimony whereof I have hereunto set my hand in the presence of two subscribing witnesses.
